(57) **CLAIM**

The ornamental design for a loudspeaker, as shown and described.

DESCRIPTION

FIG. 1 is a front isometric view of a loudspeaker, showing my new design;

FIG. 2 is a rear isometric view thereof;

FIG. 3 is a bottom isometric view thereof;

FIG. 4 is a right side elevation view thereof;

FIG. 5 is a top plan view thereof;

FIG. 6 is a left side elevation view thereof;

FIG. 7 is a bottom plan view thereof;

FIG. 8 is a rear elevation view thereof; and,

FIG. 9 is a front elevation view thereof.

The broken lines shown in the figures illustrate the portions of the loudspeaker that form no part of the claimed design.
